UNITED STATES PATENT OFFICE.

WILLIAM C. SCHULTS, OF BROOKLYN, NEW YORK.

SKIMMER BOAT.

Application filed August 13, 1925. Serial No. 50,079.

This invention relates to marine craft, and has particular reference to a skimmer boat.

The invention broadly comprehends a boat which is constructed in such a manner and adapted to be propelled, as to skim over the surface of the water, whereby it will afford the least possible resistance in order to obtain a maximum speed from a minimum motive power.

The invention furthermore contemplates a skimmer boat which in addition to embodying a hull of a shape to cause a lift to be exerted thereon by its forward movement through the water, makes use of a planing surface of general aerofoil design for exerting an auxiliary lifting action by the movement of said planing surface through the air.

As a further object the invention comprehends a skimmer boat in which the hull design is of greater width or beam dimension than of length or fore-and-aft dimension, with a downwardly and rearwardly inclined bow to afford a water planing surface operable by the forward movement of the vessel to effect a climbing or lifting action of the hull for decreasing the draft of the vessel to a minimum.

As a further object the invention includes means consisting of a plurality of parallel laterally spaced keels for maintaining a true course while minimizing "side slip".

The invention embodies as a further object in a skimmer boat, adjustable means for obtaining a fore-and-aft trim to compensate for variation in the speed, weight of the cargo, or weather conditions.

Another object of the invention resides in the provision of a combination air and water drive propulsion mechanism with means for selectively employing either at the option of the pilot.

Another object of the invention resides in the provision of an improved steering means consisting of a combination air and water rudder by virtue of which the craft may be effectually guided or steered when traveling at low or high speeds.

The invention furthermore comprehends a boat of the character set forth which is comparatively simple in its construction, inexpensive to build and operate, and which is highly efficient in its purpose.

With the above recited and other objects in view, reference is had to the following

specification and accompanying drawings in which there is exhibited one example or embodiment of the invention which is in no way intended as a limitation upon the scope of the appended claims as it is to be clearly understood that variations and modifications which properly fall within the scope of said claims may be resorted to when found expedient.

In the drawings:

Figure 1 is a perspective view of a boat constructed in accordance with the invention;

Fig. 2 is a plan view thereof;

Fig. 3 is a side view of the same;

Fig. 4 is a transverse sectional view through the main hull taken approximately on the line 4-4 of Fig. 5;

Fig. 5 is a fragmentary sectional plan view of the main hull of the vessel;

Fig. 6 is a fragmentary side view of the propulsion mechanism.

Referring to the drawings by characters of reference, 10 designates the main hull which is of greater width or beam dimension than of length or fore-and-aft dimension, the same being provided with a forwardly and upwardly inclined bow 11 extending from the substantially flat bottom 12. The bottom 12 is provided with a plurality of parallel transversely spaced longitudinally extending keels 13 for the purpose of maintaining the hull in a true course and for reducing to a minimum "side slip". The hull is provided with a continuous gunwale 14 extending inwardly and upwardly at an incline to reduce, as far as possible, wind and air resistance to the movement of the vessel while serving in its usual capacity, as a means for preventing the shipping of water.

Supported from the hull 12 by uprights 15, is a plane 16 of general aerofoil shape which upon forward movement of the vessel functions as an auxiliary lifting means for maintaining the hull in a raised position relative to the surface of the water, combined with the general lifting or raising action set up by the inclined bow and greater beam dimension.

In order to provide means for steadyng the main hull against pitching, a tail hull or pontoon 17 is provided, which is in the nature of a closed hollow body of general sled shape and having an upwardly and forwardly inclined or curved bow 18 extend-

ing from the flat bottom 19, which is also provided with a keel 20. The tail hull or pontoon 17 is connected for longitudinal sliding movements with the slide rails 21 of a framework extending rearwardly from the main hull 11. As illustrated, the connection between the pontoon 17 and the side rails consists of a member 22 bolted as at 23, to the medial portion of the pontoon and provided at its opposite sides with bearing slots 24 embracing the side rails. At its opposite sides the pontoon has flexibly connected therewith, by flexible elements 25, fore-and-aft slide collars 26 and 27 for the purpose of 10 steadyng the pontoon and limiting turning movement thereof with respect to the side rails 21.

In order to provide means for effecting longitudinal adjustment of the pontoon on 20 the side rails 21 to obtain the proper fore-and-aft trim on the main hull to compensate for variations in the weight of the cargo, weather conditions, or for other reasons, a cable 28 is attached to the forward side of 25 the member 22 and leads to the main hull for drawing the pontoon in a forward direction. A cable 29 is attached to the rear side of the member 22 and is trained around a pulley 30 carried by the rudder-bearing post 31 which is in turn attached to the rear cross bar 32 of the side rails 21. The cable 29 leads to the main hull whereby a pull exerted thereon will effect a movement of the pontoon in a rearward direction. A vertical 35 rudder shaft 33 is journaled in the bearing post 31 and has secured to its upper and lower ends, respectively, the air rudder 34 and water rudder 35. The rudder shaft 33 has secured thereto a cross arm 36, to which 40 is connected the steering rods 37 leading to the main hull. In order to brace the rearwardly projecting framework, guy wires 38 extend from the main hull 10 to the rear ends of the side arms 21.

45 The propulsion mechanism consists of a motor 40 mounted in the main hull, the motor shaft 41 of which is operatively connected by a sprocket-and-chain connection 42 or the equivalent, to a countershaft 43, upon 50 which sprockets 44 and 45 are loosely mounted, the former being connected by a sprocket chain 46 to a sprocket 47 on the water propeller shaft 48, which shaft has secured thereto a water propeller 49. The sprocket 55 is operatively connected by a sprocket chain 50 to a sprocket 51 on the air propeller shaft 52, which shaft has secured thereto an air propeller 53. The sprockets 44 and 45 are formed with clutch teeth 54 and 55, and 60 a sliding clutch element 56 having complementary clutch teeth 57 and 58 is splined on the countershaft 43 and is movable into selective engaging relation with either the clutch teeth 54 of the sprocket 44 or the 65 clutch teeth 55 of the sprocket 45, for selec-

tively driving the water or the air propeller.

In operation, the vessel when driven forwardly at a high rate of speed by the air propeller 53, is caused to lift or raise whereby it skims over the surface due to the lifting or raising action set up by the shape of the hull 10 and the auxiliary lifting power of the air planing surface 16. The plane 16 also serves in the capacity of a cover or roof for the main hull to protect the crew, 75 passengers and cargo from the elements.

What is claimed is:—

1. A skimmer boat including a main hull of greater width than length, having a forwardly and upwardly inclined bow adapted 80 upon forward motion of the boat to effect the lifting of the same upon the surface of the water, and a superposed air planing element of general aerofoil shape to constitute an auxiliary lifting means for raising and 85 maintaining the hull on the surface of the water.

2. A skimmer boat including a main hull of greater width than length, having a forwardly and upwardly inclined bow adapted 90 upon forward motion of the boat to effect the lifting of the same upon the surface of the water, a superposed air planing element of general aerofoil shape to constitute an auxiliary lifting means for raising and 95 maintaining the hull on the surface of the water, a rearwardly extending framework from the hull, and a longitudinally adjustable pontoon carried thereby for obtaining a fore-and-aft trim of the hull.

3. A skimmer boat including a main hull of greater width than length, having a forwardly and upwardly inclined bow adapted upon forward motion of the boat to effect the lifting of the same upon the surface of the water, a superposed air planing element of general aerofoil shape to constitute an auxiliary lifting means for raising and maintaining the hull on the surface of the water, a rearwardly extending framework 105 from the hull, a longitudinally adjustable pontoon carried thereby for obtaining a fore-and-aft trim of the hull, and means extending from the hull and connected with said pontoon for effecting longitudinal adjustments thereof from the hull.

4. A skimmer boat including a main hull of greater width than length, having a forwardly and upwardly inclined bow adapted upon forward motion of the boat to effect the lifting of the same upon the surface of the water, a superposed air planing element of general aerofoil shape to constitute an auxiliary lifting means for raising and maintaining the hull on the surface of the water, a rearwardly extending framework 120 from the hull, a longitudinally adjustable pontoon carried thereby for obtaining a fore-and-aft trim of the hull, means extending from the hull and connected with said pon- 125

toon for effecting longitudinal adjustments thereof from the hull, and steering means carried by the rear end of said framework.

5. A skimmer boat including a main hull 5 of greater width than length, having a forwardly and upwardly inclined bow adapted upon forward motion of the boat to effect the lifting of the same upon the surface of the water, a superposed air planing element 10 of general aerofoil shape to constitute an auxiliary lifting means for raising and maintaining the hull on the surface of the water, a rearwardly extending framework from the hull, a longitudinally adjustable 15 pontoon carried thereby for obtaining a fore-and-aft trim of the hull, means extending from the hull and connected with said pontoon for effecting longitudinal adjustments thereof from the hull, and steering 20 means carried by the rear end of said framework, comprising a vertical shaft turnable from the hull and provided with an air rudder disposed above the surface of the water and a water rudder submerged therein.
- 25 6. A skimmer boat including a main hull of greater width than length, having a forwardly and upwardly inclined bow adapted upon forward motion of the boat to effect the lifting of the same upon the surface of the water, a superposed air planing element 30 of general aerofoil shape to constitute an auxiliary lifting means for raising and maintaining the hull on the surface of the water, a rearwardly extending framework 35 from the hull, a longitudinally adjustable pontoon carried thereby for obtaining a fore-and-aft trim of the hull, means extending from the hull and connected with said pontoon for effecting longitudinal adjustments thereof from the hull, steering means carried by the rear end of said framework, comprising a vertical shaft turnable from 40 the hull and provided with an air rudder

disposed above the surface of the water and a water rudder submerged therein, and a 45 propelling mechanism including water and air propellers, a motor, and means for selectively coupling said propellers with the motor.

7. A boat including a main hull of greater 50 width than its length, having a flat bottom provided with a forwardly and upwardly inclined bow and formed on said flat bottom with transversely spaced parallel longitudinally extending keels, a continuous upwardly 55 projecting inwardly inclined gunwale at the upper edge of the hull, a rearwardly spaced longitudinally adjustable pontoon connected with the hull for effecting a fore-and-aft trim, and an air planing element carried by 60 the hull in superposed relation thereto to constitute a covering top and functioning in combination with the shape of the hull, to raise the same with respect to the surface of the water upon forward movement 65 of the hull.

8. A boat including a main hull of greater width than its length, having a flat bottom provided with a forwardly and upwardly 70 inclined bow and formed on said flat bottom with transversely spaced parallel longitudinally extending keels, a continuous upwardly 75 projecting inwardly inclined gunwale at the upper edge of the hull, a rearwardly spaced longitudinally adjustable pontoon connected with the hull for effecting a fore-and-aft trim, an air planing element carried by the hull in superposed relation thereto to constitute a covering top and functioning in combination with the shape of the hull, to 80 raise the same with respect to the surface of the water upon forward movement of the hull, a combined air and water rudder, and selectively driven air and water propulsion means.
